UNITED STATES PATENT OFFICE.

GEORGE WHEELOCK, OF WASHINGTON CITY, DISTRICT OF COLUMBIA.

IMPROVEMENT IN THREAD-GUARDS FOR SPOOLS IN SEWING-MACHINES.

Specification forming part of Letters Patent No. **87,810**, dated March 16, 1869.

To all whom it may concern:

Be it known that I, GEORGE WHEELOCK, of Washington city, in the District of Columbia, have invented a new and useful Spool-Carrier for Sewing-Machines; and I do hereby declare that the following is a full, clear, and exact description of the same, reference being had to the accompanying drawings, which make a part of this specification, in which—

Figure 1 is a perspective view, and Fig. 2 a central section.

The object of this invention is to provide a remedy for the inconvenience occasioned by the thread running from the spool, when full, onto the spindle, when it becomes tangled and breaks, thus causing stoppage and much inconvenience and delay in the operation of sewing.

The necessity for this invention will be at once conceded by all who have been accustomed to much sewing.

It consists in so inclosing the spool, especially when full, in two cone or cup-shaped heads, which cause the unwinding thread to incline toward the middle of the spool instead of being allowed to kink off at the ends, which it is so liable to do from the twist in the thread.

f is the spindle of the machine, onto which may first be put a small tube to form a shoulder, against which the thimble of the cup *a a'* works, which thimble extends quite through the spool, and may be seen prolonged at *d*. It also has two springs, *g g'*, soldered or struck

from same piece to it to hold the spool centrally, or so that the spool will be held firmly.

After the spool-thimble *d* is in place and so adjusted as to turn smoothly and freely on the spindle *f* the thimble *e* is placed tightly on the spindle *f* in front of thimble *d*, which thimble *e* performs the office of a washer, against which thimble *d* turns. These parts may be regarded as permanent fixtures. The spool is now slipped on over thimble *e* onto *d* and against the disk or cup *a a'*, where it is held by springs *g g'*. The spool is followed by a conical cup or disk, *b*, the thimble *b'* of which is large enough to slip over the thimbles *d* and *e*. The concave sides of the cups are toward each other, as represented.

For larger spools, I prefer two cups more concave, so as to allow about the same distance between the edges.

In using the device it is only necessary to remove cup *b* to remove the spool.

Having described my invention, what I claim is—

1. The conical cups *d b*, in combination with thimbles *d b'*, substantially as and for the purpose set forth.

2. Thimbles *d* and *b*, in combination with cups *a* and *b*, springs *g g'*, and thimble *e*, as described and set forth.

GEO. WHEELOCK.
